DRIER

Charles W. Keatley, Castle Shannon, Guy V. Woody, Mount Lebanon, and Collier H. Kear, Dormont, Pa., assignors to Koppers-Rheolaveur Company, a corporation of Delaware

Application February 21, 1931, Serial No. 517,446

20 Claims. (Cl. 210—68)

This invention relates to driers of the type disclosed in Patent No. 1,650,427 granted November 22, 1927 to Howard B. Carpenter, and the present invention has been developed in order to simplify and improve the construction and operation of this type of drier.

One object of the invention is to decrease the air or wind resistance of the rotary screen, thereby reducing the amount of power required for driving the same.

Another object is to provide improved sealing joints between the rotary screen and stationary parts of the casing to prevent the escape of material between the casing and the screen.

Still another object is to provide means for retaining on the screen plates a pad or bed of the material being dried.

A further object is to prevent excessive wear of the casing due to the impact of the material finally discharged from the rotary screen.

A still further object is to improve the construction and operation of the effluent discharge sluice-way.

Other objects and features of novelty will be apparent as the following description proceeds, reference being had to the accompanying drawings, in which

Figure 1 is a view largely in section and partly in elevation of a drier embodying the improvements according to the present invention;

Fig. 2 is a detail section showing the preferred embodiment of the sealing joint between the feed hopper and the rotary screen;

Fig. 3 is a detail section showing the improved sealing arrangement for the bottom of the screen, and the wear plate for receiving the impact of the particles;

Fig. 4 is an enlarged detail section through the rotary screen adjacent one of the reinforcing ribs, showing the improved arrangements for decreasing the wind resistance, and for mounting the screen plates and material retaining flange;

Fig. 5 is a top plan view of the structure shown in Fig. 4;

Fig. 6 is a bottom plan view of the same;

Fig. 7 is a vertical section through the outer wall of the casing;

Fig. 8 is a detail of the supporting member which carries the screen plates and the material retaining flange;

Fig. 9 is a section taken along the line IX—IX of Fig. 8;

Fig. 10 is a detail of the material retaining flange;

Fig. 11 is an enlarged detail section through

adjacent portions of the hopper and rotary screen, showing a modified hopper sealing means, and the mounting of the upper screen plate; and

Fig. 12 is a view similar to Fig. 3, showing the arrangement for retaining an impact cushioning bed of material on the casing wall adjacent the bottom of the rotary screen, as a modified expedient for preventing excessive wear.

Referring more particularly to the drawings, the drier disclosed in Fig. 1 comprises essentially a stationary casing 10 and a rotary screen 11. In the form shown, the casing 10 comprises a top member 12 which forms a cover for the casing, and is provided with a hopper 13. Below the top 12, flanged and bolted thereto is an outer side 70 wall 14.

Within the side wall 14 is mounted an inner wall 15 which is spaced therefrom by a flange 16 bolted to a corresponding flange on the outer wall 14. Below the flange 16, the inner wall is 75 flanged and bolted to the upper flange of a supporting member for the entire structure. This member is preferably a channel 17, although an I-beam structure may be used in some installations. At this point is secured the top of a discharge chute 18 which delivers the dried material to a conveyor 19.

For supporting and rotating the screen 11 a vertical shaft 20 is provided, the upper end of which is mounted in a conventional bearing not 85 shown, and provided with suitable driving means. A lower bearing 22 is being carried by a spider 23, the outer ends of which are bolted as at 24 to internal lugs of the inner casing wall 15.

The rotary screen 11 comprises upper and lower spiders 27 and 28, which are keyed to the shaft 20. The arms of the upper spider 27 terminate in a conical rim 29, having peripheral lugs 30. The lower spider 28 is keyed to the shaft 20 slightly above the bearing 22. The ends of the spider arms carry a lower base ring 32, being preferably cast integral therewith.

The peripheries of the spiders 27 and 28 are connected by a plurality of rib members 34, arranged generally in the form of a pyramid, being disposed in spaced relation. The ends of the rib members 34 terminate in pads 35, the upper pad being bolted to the lugs 30 and the lower pad being bolted to the rim 32.

The rib members 34 are provided with offsets 37 therein, which offsets give the rib members a stepped configuration. In cross-section, the rib members 34 are preferably T-shaped, the flanges of the T being disposed toward the inner side 110

of the rotary screen, and the web thereof projecting radially outwardly therefrom.

Fitted to the inner side of the rib members 34, above and below the offsets 37, are a plurality of screen plates 39. While various kinds of foraminous material may be employed for this purpose, perforated chromium alloy steel plates have been found very satisfactory in operation. The screen plates 39 are frusto-conical sections, and when fitted to the ribs 34 in the manner described above, these plates 39 form a series of stepped frusto-conical screens.

The entire screen surface and the load of material carried thereby, are supported by the rib members 34 which span the space between the upper and lower spiders of the rotor. The rotary screen develops a very high speed during the drying process, and the consequent centrifugal force results in a heavy load on the ribs 34 acting as beams. For this reason, the web of the T section thereof has heretofore been made very deep. This is undesirable, as the depth of this web projects transversely to the direction of rotation and results in an enormous wind resistance to the rotation of the screen.

In order to decrease the depth of this flange 36 and thereby decrease the wind resistance, without sacrificing the strength necessary to withstand the centrifugal force developed, there has been provided a plurality of reinforcing rings 40. The mounting of these members is shown in detail in Figs. 4 and 5 as being associated with the corresponding offsets 37 in the rib members.

Being continuous around the rotor, these rings 35 reinforce the rib members to such an extent that the depth of the web 36 may be materially decreased, the load heretofore taken thereby being taken by tension in the ring members 40. The web 36 is notched as at 42 to receive the ring 40 and this web is also bossed as at 43 to receive a retaining bolt 44 for the ring.

For supporting the screen plates 39, members 45 are carried by the ribs 34, extending between corresponding offsets 37 in the ribs 34. Details 45 of a member 45 are shown in Figs. 8 and 9. This member is preferably a casting in the form of a Z-bar, having flanges 46 and 47 connected by a web 48. The Z-bar member is curved in such a manner that the flanges 46 and 47 and web 48 thereof are conical surfaces. The ends of the flanges 46 and 47 are notched away, leaving the web projecting at each end, as at 49.

The portions 49 are fitted under the offsets 37 and secured by screws 50 to the flanges of the 55 T rib 34, the notched portions of the flanges 46 and 47 serving to clear the flanges of the T rib. The inner upper flange 47 forms a base to which is secured, by means of bolts 51, the lower margin of the screen plate 39 above the offset 37.

60 The lower outer flange 46 forms a base to which is secured the upper margin of the screen plate 39 therebelow by means of bolts 52. Thus the member 45 serves as a rigid supporting base and attaching means for the adjacent screen plates 39.

65 The member 45 also serves as a support for a retaining flange 53 associated with each of the offsets 37. This flange serves to retain a pad or bed of material thereabove on the screen plate. This pad of material has several important functions.

70 There has been a tendency for the liquid to flow on down the inside of the conical screen, instead of passing therethrough. The pad of material above the flange 53 absorbs the water and 75 thus retains the same, to facilitate the action of

centrifugal force in causing the water to be forced through the perforations.

Furthermore, the pad of material retained by the flange 53 acts as a filter bed to retain the fines and thus improve the separation. This pad 80 of material also acts to cushion one screen against impact thereagainst of material from a screen thereabove, and serves to protect the screen plate from consequent rapid wear.

The member 45 provides a very convenient 85 means for attaching the flange 53. As shown in detail in Fig. 10, this flange 53 is notched as at 54 to receive bolts 55 whereby the flange is adjustably secured to the web 48 of the Z-bar 45. Thus the flange 53 may be moved in or out as 90 desired, in order to adjust the depth of the cushioning bed of material retained on the screen 39.

Intermediate the flanges 53, smaller annular angles 56 are secured to the screening material in any desired manner, as by bolting, riveting or 95 welding, and they serve to retain smaller beds of material for the same purposes. These angles also reinforce the screen between the supports 45.

With driers of this type heretofore employed, there has been considerable leakage between the 100 hopper 13 and the upper spider rim 29 of the screen. The centrifugal force developed has had a tendency to project the material received from the hopper 13 out through the space between the hopper and the rim 29.

To improve this condition, there has been developed the structure shown in detail in Figs. 2 and 11. The form shown in Fig. 2 is preferred, but the modification shown in Fig. 11 effectively 105 prevents any leakage.

As shown in Fig. 11, a conical plate 57 is secured by screws 58 to the bottom of the hopper 13. The hopper 13 being conical, the plate 57 is normal thereto at all points, forming an annular groove, which conforms to the upper rim of the 115 screen element.

The hopper part 13 fits over, and the plate 57 snugly underlies the upper edge of the rim 29 and extends therebelow a sufficient distance to prevent escape of material fed by the hopper 13. 120 Thus the clearance between the parts is so arranged that the direction of action of the centrifugal force is opposed to the direction of movement of the material necessary for the escape thereof.

The preferred form shown in Fig. 2 preserves 125 all of the advantages mentioned above, and also facilitates assembly of the machine. In lieu of the plate 57, a ring member 59 is provided, which has a cylindrical face engaging a cylindrical face 130 of the hopper 13. This arrangement permits vertical adjustment of the sealing flange, the bolt holes being enlarged or elongated for this purpose. Thus a uniform and accurate clearance may be maintained after the machine is assembled.

As shown in detail in Fig. 3, an improved arrangement is provided for sealing the joint between the bottom of the rotary screen and the inner casing wall 15. The upper rim of the inner 140 casing wall 15 is formed by an inwardly directed flange 60, and the rim 32 is T-shaped in cross section. The outer flange of the T-section overlies the flange 60 and the web 61 of the T-section depends below the edge of the flange 60. Thus 145 an annular groove is formed, which fits over the edge of the flange 60.

Here the clearance between the parts is perpendicular to the direction of action of the centrifugal force. The web 61 of the rim 32 not only 150

serves to improve the seal with the casing wall 15, but also serves as an abutment to support the lower edge of the screen plates 39. The screen plates 39 are notched out to clear the ends 5 of the spider arms 31 where they join the rim 32.

The wear due to impact of particles under the great amount of centrifugal force developed in this type of drier has been detrimental to portions of the casing. One expedient for protecting 10 the casing is shown in Fig. 12. A flange 62 projects inwardly from the casing wall 16 a short distance below the flange 60 and forms an annular chamber therebetween. This chamber is intended to receive material thrown off the lower 15 edge of the screen plate 39, and retain a sufficient amount thereof to form a cushioning bed, so that the impact of later particles will not result in serious wear upon the casing wall 15.

The preferred construction for contending with 20 this condition is shown in Fig. 3. In lieu of the flange 62, wear plates 63 of harder metal are provided, which form a liner for the casing wall 15 below the flange 60.

The inner surfaces of the wear plates are 25 smoothly rounded so as to deflect the material downwardly toward the discharge chute 18. The plates 63 are secured to the wall 15 by bolts 64. The segmental construction thus afforded facilitates installation and replacement of the protective liner formed thereby.

The structure shown in Fig. 7 facilitates the removal of the effluent material from the casing after it has been thrown off by the screen. The lower portion of the outer casing wall 14 is 35 conical as shown at 65, and as the inner casing wall 15 is vertical, this tapering of the outer wall 14 results in a restricted channel at the bottom of the chamber therebetween.

Furthermore, the conical portion 65 carries a 40 plurality of inwardly projecting spiral flanges 66, each of which begins at a thin edge 67 at the bottom of the wall 14 and extends upwardly along the portion 65 to a high point 68. From the point 68 the flange depends vertically as at 69 45 leaving a space 70 between the portion 69 and the adjacent edge 67 of the next flange. There are four flanges 66 equally spaced around the inner face of the outer casing wall 14.

In view of the tapered character of the conical 50 portion 65, the spiral flange is wider at the high portion 68 than at the lower edge 67. Thus the channel formed by the portion 65, spiral flange 66 and the outer surface of the inner wall 16 is restricted in two directions. This construction 55 materially increases the velocity of travel of effluent material to the space 70 which forms a discharge aperture. Below each aperture 70 a discharge chamber 71 is provided for connection to a discharge pipe 72.

The increase in velocity due to the tapering 60 passage is important inasmuch as the effluent liquid generally contains a certain amount of sludge which would tend to clog the passage without this increased velocity provision. If extraordinary conditions demand further aid in the 65 discharge of the effluent material, water pipes 73 may be provided as shown in Fig. 5 to direct a jet of water downwardly along the upper surface of the flange 66 and thus wash down any sludge thereon.

While the features of novelty disclosed herein 75 are in the nature of improvements on a known type of drier, nevertheless the improvements are of major importance inasmuch as they determine the commercial success or failure of the

drier. Furthermore, the various improvements cooperate with each other in such manner as to greatly improve the whole. Therefore, while the improvements have been described in considerable detail, the scope of the invention is not to be limited to the exact details disclosed, but instead embraces such embodiments of the disclosed ideas as fall within the scope of the appended claims.

We claim as our invention:

1. In a drier, a downwardly and outwardly tapering rotary frusto-conical screen, and an annular flange projecting inwardly from said screen and adapted to retain on said screen a bed of the material being dried the inner end of said flange being normal to said screen.

2. In a drier, a rotary screen comprising downwardly stepped surfaces of screening material, and a flange for retaining a bed of material on one of said screen surfaces to cushion the impact of the material discharged thereon from another screen surface, the inner end of said flange being normal to said screen.

3. In a drier, a rotary screen comprising rib members having offset portions formed therein, 100 annular reinforcing rings connecting said offset portions, and screening material rigidly secured to and reinforced annularly by said reinforcing rings.

4. In a drier, a rotary screen comprising rib members having offset portions formed therein, 105 annular reinforcing rings connecting said offset portions, and frusto-conical screening material rigidly secured to and reinforced annularly by said reinforcing rings between rib members 110 and between said offset portions.

5. In a drier, a rotary screen comprising an upper rim, a lower rim, rib members connecting said rims and having offsets formed therein, annular members connecting corresponding offsets of adjacent rib members, frusto-conical screen plates secured to adjacent annular members, a flange projecting inwardly normal to said screen plate, and an adjustable mounting for said flange on one of said annular members to permit adjustment of the inward projection thereof.

6. In a drier, a stationary casing part, a rotary frusto-conical screen part mounted to rotate therein, one of said parts having an annular groove, and the other part having an annular rim conforming to said groove, whereby the clearance therebetween is transverse to the direction of centrifugal force due to rotation of said screen part, and means for adjusting one of said parts to conform to the other of said parts.

7. In a drier, a stationary frusto-conical hopper, a rotary frusto-conical screen and an annular member carried by said hopper and having a flange underlying the upper rim of said rotary screen, said annular member being adjustable 125 from the exterior of said hopper and screen.

8. In a drier, a rotary screen having an annular rim and a casing having an inwardly projecting flange underlying said rim, said casing having a second inwardly projecting flange 140 spaced therebelow and defining therebetween a chamber for retaining a shock absorbing cushioning bed of material being screened therein between the casing and the annular rim in the path of subsequent material discharged therefrom.

9. In a drier, a chamber having an annular wall, the lower portion of said wall being conical and provided with an inwardly directed spiral flange decreasing in width towards the bottom of the spiral as said conical wall decreases in 150

- diameter, and a confining wall for said spiral flange forming therewith and with the conical wall a downwardly directed effluent channel gradually decreasing in cross-section towards the bottom of the spiral to effect an acceleration in velocity of effluent flowing therethrough.
10. In a drier, a rotary screen, a casing having inner and outer annular walls, said inner wall having an inwardly directed flange projecting 10 into an annular groove in the lower rim of said screen, and a flange therebelow forming therewith a material retaining chamber, one of said walls having spiral flanges each extending to the other wall and forming therewith an annular 15 series of effluent sluice-ways having inclined bottoms, with discharge ports at their lower ends, and one of said walls being conical and thereby gradually narrowing the sluice-ways so as to decrease their cross-sectioned area towards the 20 discharge ports to increase the rate of flow of effluent along the flanges.
11. In a drier, a rotary screen, a casing having inner and outer walls, said inner wall having an inwardly directed flange in sealing engagement 25 with the lower edge of said rotary screen, one of said walls having a spiral flange extending to the other wall and forming therewith an effluent sluice-way having an inclined bottom, and means 30 for directing a jet of fluid onto said spiral flange to wash down sludge thereon.
12. In a drier, a casing, a rotary frusto-conical screen in said casing comprising upper and lower rims, rib members connecting said rims and having offset portions therein, annular elements 35 connecting said offset portions, frusto-conical screening material carried by said annular elements between said rib members and between said offset portions, annular flanges adjustably secured to said annular elements and projecting 40 inwardly therefrom normal to said screening material to retain a bed of material thereon, annular reinforcing rings outside of said rib members and secured thereto adjacent said offsets, and means for preventing escape of the 45 material being dried between said screen and the adjacent rims of said casing.
13. In a drier, a rotary frusto-conical screen comprising an upper circular rim, a larger circular lower rim, and rib members connecting said 50 rims and converging toward said upper rim, said rib members having offset portions in a plane parallel to said rims, and a reinforcing ring secured to the upper outer side of said offset portions.
- 55 14. In a drier, a rotary frusto-conical screen comprising an upper circular rim, a larger circular lower rim, and rib members connecting said rims and converging toward said upper rim, said rib members having offset portions in a 60 plane parallel to said rims, an annular member connected to the underside of the offset portions of two adjacent rib members, an inwardly projecting flange secured to said annular member and having slots therein, and means passing 65 through said slots for adjustably securing said flange to said annular member.
15. In a drier, a rotary frusto-conical screen comprising an upper circular rim, a larger circular lower rim, and rib members connecting said rims and converging toward said upper rim, said rib members having offset portions in a plane parallel to said rims, an annular member connecting the offsets of adjacent rib members, an upper screen plate secured to the inner side of said annular member, and a lower screen plate secured to the outer side of said annular member. 80
16. In a drier, a rotary frusto-conical screen comprising an upper circular rim, a larger circular lower rim, and rib members connecting said rims and converging toward said upper rim, said rib members having offset portions in a plane parallel to said rims, a ring secured to the upper side of said offset portions, and an annular member secured to the under side of said offset portions. 85
17. In a drier, a rotary frusto-conical screen comprising an upper circular rim, a larger circular lower rim, and rib members connecting said rims and converging toward said upper rim, screening material secured within said rib members, an annular angle having a flange secured to said screening material and another flange projecting inwardly normal to the surface of said screening material to retain a pad of material being screened thereon over which other 90 material being screened may pass on down the screen and thereby provide for absorbing any liquid that tends to escape centrifuging and run down the screen. 95
18. In a drier, a rotary screen comprising an upper circular rim, a lower larger circular rim, rib members connecting said rims and having offset portions, a ring secured to the upper side of said offset portions, and a Z-bar connecting the under side of corresponding offset portions of adjacent rib members. 100
19. In a drier, a rotary screen comprising an upper circular rim, a lower larger circular rim, rib members connecting said rims and having offset portions, a ring secured to the upper side of said offset portions, and a Z-bar connecting the underside of corresponding offset portions of adjacent rib members and screening material secured to a flange of said Z-bar. 105
20. In a drier, in combination, a rotary frusto-conical screen comprising an upper circular rim, a larger circular lower rim, and rib members connecting said rims and converging toward said upper rim, a casing comprising a hopper in sealing engagement with said upper rim, an inner wall in sealing engagement with said lower rim, and an outer wall connected to said hopper and said inner wall, one of said walls having a spiral flange tapering in width and downwardly inclined towards a lower outlet end and extending to the other wall and forming thereby a sluice-way of gradually diminishing cross-sectional area towards the outer end. 110
